UNITED STATES PATENT OFFICE.

WILLIAM BAXTER, OF JERSEY CITY, NEW JERSEY, ASSIGNOR TO J.
ASHTON GREENE, OF BROOKLYN, NEW YORK.

WRENCH.

SPECIFICATION forming part of Letters Patent No. 281,431, dated July 17, 1883.

Application filed May 18, 1883. (No model.)

To all whom it may concern:

Be it known that I, WILLIAM BAXTER, a citizen of the United States, residing in Jersey City, in the county of Hudson and State of New Jersey, have invented certain new and useful Improvements in Wrenches, fully described and represented in the following specification and the accompanying drawings, forming a part of the same.

10 This invention relates to an improvement in the duplex wrench known as the "Baxter" wrench; and it consists in the combination with the halves of the wrench, which slide upon one another when adjusting the jaws, of tongues 15 and grooves formed upon the contiguous faces, to stiffen the handle and jaws when in use.

In the Baxter wrenches heretofore known the adjusting-screw, owing to its location at some distance from the jaws, could not prevent the jaws from straining open somewhat when in use, so that the wrench could not be so effectively used upon hexagonal as upon square nuts. The outer jaw has also been liable to breakage from the want of thickness in its 25 base; and the object of the present invention is to furnish a means of thickening one side or movable part of the wrench without weakening the other correspondingly and to prevent the yielding or straining open of the jaws when 30 in use, as heretofore.

The nature of the improvements will be understood by reference to the annexed drawings, in which—

Figure 1 is a side view of a wrench constructed therewith. Fig. 2 is an edge view projected therefrom, and Fig. 3 is an inside view of one half or part of the wrench detached from the other to exhibit the strengthening-tongues more clearly. Fig. 4 shows an alternative construction.

A is one of the two similar parts of which the wrench is constituted, and upon which are formed one inner jaw, C, and one outer jaw, D, the screw E being swiveled in a lug, l, at the 45 center and tapped into a nut, n, upon the opposite part, A. The latter part is shown in Fig. 3 with four grooves formed upon its inner face, parallel with the guides h, formerly used alone to sustain the jaws when in operation. Two 50 of the grooves, g, one formed close to the line of the guides h, and two others, i, are formed

close to the sides of the nut n. Upon the part A tongues or ribs k are formed to fit and move in the grooves, g, and by their parallelism with the guides h to resist any strain transverse to the latter. At the base of the jaws the side in which the tongue g is formed is made thicker than the opposite part, whose strength is increased by the re-enforcement of the rib or tongue k.

The difference in thickness of the parts A and B close to the jaws is plainly shown in Fig. 2, as well as the formation of the guide h and the stiffening-tongue k upon the part A, and the cutting of the groove g in the thicker 65 part B. The parts A and B may be made of uniform thickness below the jaws, as the strain upon them there is equal, and the use of the tongue and groove near the jaws sustains them in a very efficient manner; but I have shown 70 herein a further means of stiffening the wrench by the addition of tongues m beside the screw, which require the thickening of the opposite side to admit of the grooves i. At this part of the wrench the grooves may be made upon 75 either A or B to produce the same result; but the ribs are most readily formed at the edges of lug l, as shown.

From the above description it will be understood how I am able to thicken the bases 80 of the outer jaws, D, and how I prevent the springing or straining of the jaws apart, the tongues k operating to re-enforce the guides h, as well as to strengthen the thinner part of the wrench A. The tongues also operate much 85 more efficiently than the guides h in holding the jaws firmly, because they are fitted to bear at both edges in the grooves, and thus resist movement in two directions, while the guides h are fitted in open grooves, from which the 90 working strain is at liberty to pull them without resistance.

Having thus set forth the nature of my improvements, it is obvious that tongues, as g or m, may be applied at any other points than 95 those shown, and that any of the tongues shown may be used without the others.

In Fig. 4 is shown an alternative construction for the tongues, whereby they are adapted to keep the parts A and B from springing away 100 from one another. At k', in the latter figure, the tongue and groove are each shown of dove-

tail form, and at m' the tongue is formed with a side rib adapted to fit a channel formed at one side of the grooves i , and thereby hold the parts A and B closely together sidewise. If desired, the entire inner faces of both these parts may be provided with tongues and grooves, and thus be rigidly held in any position. It will be noticed that the tongues remain in the grooves during a much greater movement of the jaws than do the guides h , as the former are twice the length of the latter, and remain engaged when the guide is almost entirely inoperative. Wrenches provided with this improvement therefore operate much more effectively upon large nuts and screws than without it.

I therefore claim my invention in the following manner:

1. The herein-described wrench, comprising two movable parts or halves placed face to face

and an adjusting-screw diagonal to the said parts, the latter having guides and undercut grooves to receive the same, and additional tongues and grooves, substantially as and for the purposes set forth.

25

2. A diagonal wrench composed of two parts or halves, which slide upon one another, and a diagonal adjusting-screw, said parts or halves being provided with tongues and grooves additional to the guides and their grooves, the part containing the grooves being thickened opposite the same, substantially as described.

In testimony whereof I have hereunto set my hand in the presence of two subscribing witnesses.

WM. BAXTER.

Witnesses:

THOS. S. CRANE,
JOHN ASHTON GREENE.
